RAIL JOINT

Application filed April 11, 1931, Serial No. 529,433, and in France April 17, 1930.

Many efforts have heretofore been made to provide a rail joint adapted for connecting adjacent or abutting ends of rail sections on railroads whereby to prevent relative lateral movement of said rail sections and to overcome to a large extent their relative creeping tendency. However a large number of the rail joints proposed hitherto have not proven satisfactory or practicable for various reasons among which may be mentioned the complicated character thereof, the expense incident to manufacture and upkeep, the inefficient bracing and holding characteristics, the necessity of drilling or otherwise weakening the rail sections due to the application of the device, the loosening of the joint and resulting spreading of the rail sections in use, the large number of bolts required with the concomitant separation and loss of the latter, and also the hindrance to free thermal expansion or contraction of the rail sections due to the necessity in rail joints not held hitherto by bolts passing through the webs of the rail sections of firmly abutting and clamping said rail joints against the base of the rail sections.

It is the primary object of the present invention to overcome the above and other existing objections or defects in rail joints and allied devices as at present constructed and to this end the invention provides a rail joint of improved and simplified construction involving but a few parts, comparatively inexpensive to produce, readily applicable to and detachable from the rail sections to be jointed, and highly efficient, satisfactory and durable in use.

Another object of the invention resides in the provision of a rail joint comprising a pair of co-operating rail engaging splices or clamping members abutted in widely diverging relation to each other at the opposite undersides of the rail section heads and novel means for securing said clamping members in holding contact with the rail sections without the necessity of providing holes in, or otherwise damaging or weakening, their webs and moreover without interfering with the required thermal expansion or contraction of the rail sections.

Still another object of the invention resides in the provision of a rail joint comprising a pair of co-operating clamping members or splices abutted in widely diverging relation to each other at the opposite beveled undersides of the rail section heads so as to operate as buttresses and held invariably spaced by a stretcher located underneath the bases of the rails and braced by one or more bolts or like securing members located intermediate said stretcher and said rail bases.

Still a further object of the invention resides in the provision of a rail joint comprising a pair of co-operating clamping members or buttress-like splices or props abutted in widely diverging relation to each other at the opposite undersides of the rail section heads so as to constitute a reinforced or supporting medium for one another, thereby taking considerable strain from the rail sections themselves, which is particularly useful in case of a track on which very heavy trains travel at high speeds.

Other objects of the invention will be appreciated from the description to follow when considered in connection with the accompanying drawings which forms a part of this disclosure and wherein is shown for the purpose of illustration a convenient and satisfactory embodiment of the invention.

In the drawings:

Figure 1 is a longitudinal elevational view showing the two adjacent rail sections fitted with the improved rail joint spiked to the ties of the track, assuming said ties to be made of wood as is usual in railroad building.

Figure 2 is a top plan view corresponding to Figure 1 and showing the side lugs by which the clamping members are spiked down to the ties of the track.

Figure 3 is a cross sectional view along the line $x-x$ of Figure 2, looking in the direction of the arrow, the tie being shown in chain lines.

Figure 4 is a cross sectional view along the line $y-y$ of Figure 2, also looking in the direction of the arrow.

Like reference characters designate like parts throughout the several views.

As illustrated, the improved rail joint is

made up primarily of a pair of symmetrically arranged clamping members constituted by angle fish plates or splices advantageously made of highly resistance steel. Each of these clamping members comprises three integrally cast or machined parts: first an obliquely extending buttress plate 1 abutted against the beveled underside of the heads A, A' of the adjacent rail sections and terminating short of the top face of the ties C, C, secondly, a vertically extending skirt 5 of a length shorter than that of the buttress plate 1 and so sized as to loosely fit into the space between the two consecutive ties C, C spanned by the rail joint and, thirdly, a pair of horizontally extending lugs 11 resting upon the top face of the respective ties C, C and firmly secured thereto by spikes 9 engaging through holes 12 formed in said lugs and having heads 10 bearing on said lugs.

The obtuse angle formed by the oblique buttress plate 1 and the substantially horizontal lugs 11 is preferably comprised between 110° and 145° but may vary of course depending on the cross sectional shape of the rail sections to be coupled.

Aligned with the side edges of the skirt 5 are narrow vertical slots 1^a extending over a small portion of the buttress plate 1 for giving the buttress-and-skirt unit a slight flexibility or resiliency sidewise for a purpose that will appear hereafter.

The two clamping members or splices 1—5—11 of which the rail joint is made up are arranged symmetrically to the webs of the rail sections, as shown by Figures 3 and 4, and are held invariably spaced by a rigid stretcher or strut 6 advantageously constituted by a piece of shaped steel comprising a rectangular bottom plate and integral convergent tapering wings of trapezoidal outline bent down at their free upper ends to form hooks 6^a. The stretcher is thus, viewed in perspective, channel-shaped and acts as a fulcrum.

The depending skirt 5 of each clamping member 1—5—11 is formed, in the constructional form shown, with a pair of spaced holes through which are respectively engaged a pair of bolts 7 terminally fitted with nuts 8. The number of such bolts may vary, for example depending on the distance between the two consecutive ties C, C. Easy access to the nuts 8 may be had due to said nuts being located in the open space between the ties on both sides of the gap B between the rail sections A, A'. Thus a spanner or wrench may be easily introduced to get hold of the nuts 8 when it becomes necessary to tighten or loosen the said nuts.

The rail sections are clamped as usual to the ties C, C by screw-threaded spikes D of conventional form which imprison the rail bases between the spike heads and the ties. Such spikes D are shown in the drawings as

engaged in those particular ties fitted with the spikes 9—10 which serve to hold down the lugs 11 of the novel clamping members or splices but should this arrangement be found to weaken the ties excessively, especially in the case of wooden ties, the spikes D may be done away with in each of said particular ties.

To assemble the rail joint, each clamping member 1—5—11 is first placed in operative position as shown in Figures 3 and 4, the bolts 7 being engaged in the holes in the skirts 5 whereupon the upper hooks 6^a of the fulcrum stretcher 6 are engaged over said bolts. By then tightening the nuts 8, the skirts 5 and buttress plates 1 which, due to the slots 1^a, possess a certain resiliency sidewise are forced towards each other, the upper ends of the buttress plates 1 becoming firmly wedged into the grooved or beveled undersides 2 of the rail section heads A, A'. When the nuts 8 have thus been thoroughly tightened for example by means of a box wrench such as the one commonly used by railroad workers, the screw-threaded spikes 9 are inserted into the holes 12 formed in the side lugs 11 and driven home till the heads 10 of said spikes contact with said lugs and hold the latter in invariable position with respect to the ties C, C.

It will be appreciated that due to the holding stress produced by the bracing bolts 7 exercising itself at right angles to the holding stress ensured by the spikes 9, any displacement of the clamping members or splices 1—5—11 is precluded in any direction irrespective of the strains transmitted thereto by the rail sections.

It will thus be seen that the invention provides a rail joint of simple and rugged structure which permits holding the adjacent or abutting rail sections invariably while preventing any lateral displacement or creeping and while also saving said rail sections from the dangerous breakages as are caused at present by the weakening due to bolts being engaged through the webs of most rails of existing railroads.

Numerous minor constructional details such for example as the size and shape of the skirts 5 or lugs 11 and the number of bolts 7 or spikes 9 might of course be changed without departing from the scope of the invention as set forth in the subjoined claims.

What I claim is:

1. A rail joint for railroads comprising, in combination, a pair of co-operating clamping members arranged symmetrically to the adjacent rail sections and each integrally made up of a buttress plate slanting off the underside of the heads of said rail sections, side abutments bearing on the top faces of the track ties spanned by the joint, and a skirt depending in the space between said ties, a rigid stretcher located in said space underneath the bases of the rail sections and hold-

ing the companion skirts invariably spaced, and bracing means intermediate the stretcher and rail section bases for firmly clamping said skirts together.

5 2. A rail joint for railroads comprising, in combination, a pair of co-operating clamping members arranged symmetrically to the adjacent rail sections and each made up of a buttress plate steeply slanting off the under-
10 side of the heads of said rail sections, side abutment lugs flatly bearing on the top faces of the track ties spanned by the joint, and a skirt depending in the space between said ties, a rigid fulcrum stretcher located in said
15 space below the bases of the rail sections and holding the companion skirts invariably spaced, and transverse bolts intermediate the stretcher and rail section bases for firmly clamping said skirts together.

20 3. A rail joint for railroads comprising, in combination, a pair of co-operating clamping members arranged symmetrically to the adjacent rail sections and each integrally made up of a buttress plate steeply slanting
25 off the underside of the heads of said rail sections, side abutment lugs delineating an obtuse angle with said buttress plate and flatly bearing on the top faces of the track ties spanned by the joint, and a skirt depending
30 in the space between said ties, a rigid fulcrum stretcher located in said space below the bases of the rail sections and holding the companion skirts spaced invariably, and transverse bolts intermediate the stretcher and rail section
35 bases for firmly clamping said skirts together.

4. A rail joint for railroads comprising, in combination, a pair of co-operating clamping members arranged symmetrically to the adjacent rail sections and each integrally made up of a buttress plate steeply slanting off the underside of the heads of said rail sections, side horizontally protruding lugs delineating an obtuse angle with said buttress plate and flatly bearing on the top faces of the track ties spanned by the joint, and a skirt depending in the space between said ties, a rigid fulcrum stretcher located in said space below the bases of the rail sections, said
50 stretcher comprising a rectangular bottom plate holding the companion skirts spaced invariably, and upwardly directed tapering wings having their upper edges bent down to form hooks, and transverse bolts engaging through the stretcher hooks and firmly bracing said skirts together.

5. A rail joint for railroads comprising, in combination, a pair of co-operating clamping members arranged symmetrically to the adjacent rail sections and each integrally made up of a buttress plate steeply slanting off the underside of the heads of said rail sections, side horizontally protruding lugs delineating an obtuse angle with said buttress plate and formed with holes receiving

spikes anchoring said lugs to the underlying track ties spanned by the joint, and a skirt depending in the space between said ties, short narrow slots extending upwardly into the buttress plate in alignment with the side edges of the skirt, a rigid fulcrum stretcher located in said space below the bases of the rail sections, said stretcher comprising a rectangular bottom plate holding the companion skirts spaced invariably, and upwardly directed tapering wings converging towards each other and having their upper edges bent down to form hooks, and transverse bolts engaged through the skirts and in the stretcher hooks and fitted with nuts for firmly clamping said skirts together.

In testimony whereof I affix my signature.
MARCEL LOCHE.
